(57) **CLAIM**

The ornamental design of a suppository, as substantially shown and described.

DESCRIPTION

FIG. 1 is a perspective view of a suppository in accordance with a first embodiment of the invention;

FIG. 2 is a top plan view thereof;

FIG. 3 is a bottom plan view thereof;

FIG. 4 is a left side elevation view thereof;

FIG. 5 is a right side elevation view thereof;

FIG. 6 is a back view thereof;

FIG. 7 is a front view thereof;

FIG. 8 is a perspective view of a suppository in accordance with a second embodiment of the invention;

FIG. 9 is a top plan view thereof;

FIG. 10 is a bottom plan view thereof;

FIG. 11 is a left side elevation view thereof;

FIG. 12 is a right side elevation view thereof;

FIG. 13 is a back view thereof;

FIG. 14 is a front view thereof;

FIG. 15 is a perspective view of a suppository in accordance with a third embodiment of the invention;

FIG. 16 is a top plan view thereof;

FIG. 17 is a bottom plan view thereof;

FIG. 18 is a left side elevation view thereof;

FIG. 19 is a right side elevation view thereof;

FIG. 20 is a back view thereof;

FIG. 21 is a front view thereof;

FIG. 22 is a perspective view of a suppository in accordance with a fourth embodiment of the invention;

FIG. 23 is a top plan view thereof;

FIG. 24 is a bottom plan view thereof;

FIG. 25 is a left side elevation view thereof;

FIG. 26 is a right side elevation view thereof;

FIG. 27 is a back view thereof;

FIG. 28 is a front view thereof;

FIG. 29 is a perspective view of a suppository in accordance with a fifth embodiment of the invention;

FIG. 30 is a top plan view thereof;

FIG. 31 is a bottom plan view thereof;

FIG. 32 is a left side elevation view thereof;

FIG. 33 is a right side elevation view thereof;

(Continued)

FIG. 34 is a back view thereof; and,
FIG. 35 is a front view thereof.
